UNITED STATES PATENT OFFICE.

WALTER BRANCH SWINDELL AND CECIL HENRY HOLLOWAY, OF RALEIGH, NORTH CAROLINA.

WATER-HEATER.

No. 911,087.

Specification of Letters Patent.

Patented Feb. 2, 1909.

Application filed April 27, 1908. Serial No. 429,537.

To all whom it may concern:

Be it known that we, WALTER B. SWINDELL and CECIL H. HOLLOWAY, citizens of the United States, residing at Raleigh, in the 5 county of Wake and State of North Carolina, have invented a new and useful Water-Heater, of which the following is a specification.

This invention relates to that class of water 10 heaters, in which water is forced in a thin stream upwards, and then downwards, through spirally formed chambers located in the walls of circulating chambers subjected to heat by means of which water, heated to 15 the desired temperature, is conducted to a boiler, or other receptacle.

The invention has especial reference to 20 that class of water heaters of this character, in which the water is circulated through the walls of conical heating chambers, and has 25 for its object to provide an improved water heater of this character, by means of which a constant circulation of an extended surface of water over an extended heating surface is created and maintained.

The invention consists of a water heater, and in details thereof constructed and arranged as hereinafter set forth and claimed.

Referring to the drawing, Figure 1 is a 30 view in elevation, and partly in vertical section of a water heater, constructed in accordance with this invention. Fig. 2 is a detail view of the upper end of the heater showing a slightly modified construction of this portion thereof, and Fig. 3 is a similar view but showing a further modification of one of the cap members.

In carrying out the invention a plurality of 40 conical heating and water circulating chambers are employed and as here shown consisting of two conical heating and circulating chambers 1 and 2, located adjacent to each other, and mounted in an oven 3, having ventilating openings 4. The water heater is 45 mounted on an oil stove 5, or other heating apparatus by means of suitable fastenings 6 and the heat is carried up through the bottom of the conical chambers 1 and 2, and out at their top. The heater may be provided 50 with fastenings, to secure it to a stove, or may rest on top of the stove without being fastened to it. Each of the conical heaters 1 and 2 is formed of two cones, located and spaced apart, one within the other, and open 55 at the top, and bottom, and fastened to-

gether and closed in any suitable manner, at their ends, the outer cone, forming the outer wall 7, and the inner cone, forming the inner wall 8, of the conical heating chamber.

The inner wall 8 is formed with the spiral 60 indentations or crimps 9, which bear against the outer wall 7, and form a shallow spiral water channel 10 extending from top to bottom of the conical heater, between the walls 7 and 8.

Above the open tops of the conical heaters 1, is preferably mounted in any suitable manner a cone shaped cap 11, closed at the top, and formed of two cones 12 and 13, located one within the other and spaced apart, and 70 closed at their lower edges. The inner cone 12, is formed with spiral indentations or crimps 14, forming a shallow spiral water channel 15, extending from top to bottom of the cap 11 and connecting at its lower end 75 by means of a pipe 16, with the upper end of the spiral channel 10, in conical chamber 1, and at its upper end with the upper end of spiral channel 10, in conical chamber 2, by means of a pipe 17.

It will be seen that the cap 11 is mounted 80 on the tops of the conical chambers 1 and 2, slightly above their open upper ends by means of the pipes 16 and 17. Water is admitted at the lower end of spiral channel 10 85 by means of a short pipe 18, connected to the conical chamber 1, and having a threaded end 19, for attachment of a hose pipe. Water is discharged from the lower end of the spiral channel 10, in conical chamber 2 by means of 90 a pipe 20, connected to the lower end of conical chamber 2, and a vertical pipe 21, connecting with said pipe 20, and extending above the conical chambers 1 and 2, and terminating in a curved end 22, adapted to 95 extend over the edge of the side of a bath tub. By having the water outlet 22, elevated above the conical chambers 1 and 2, the filling of the conical chambers 1 and 2 at all times with water is assured. The pipes 18 100 and 20 are each provided with a faucet 23 by means of which perfect drainage is secured. Water is admitted through pipe 18 to the lower end of spiral channel 10, and traverses upwards through said spiral channel to the top 105 of conical chamber 1, then through pipe 16, and spiral channel 15 to pipe 17 and down spiral channel 10 in conical chamber 2, to pipe 20, and from pipe 20 up pipe 21, and out at outlet 22. The water descending from 110

the top of the cap and down through the conical chamber 2, secures perfect drainage and circulation and the spiral water channel in conical chambers 1 and 2 provides both an 5 extended heating surface and constant circulation. The cap being slightly elevated above the open tops of the conical chambers 1 and 2 the heat passing through the latter is arrested by the cap, and utilized to heat it, 10 the elevation and shape of the cone giving sufficient ventilation.

In the modification shown in Fig. 2, two cone shaped caps 24, are employed, in lieu of the single cone cap 11, each of said caps being 15 constructed similarly to the cone cap 11, the caps 24, being connected at their top by a pipe 25, and being slightly elevated above and mounted on the upper ends 26, of conical heating and water circulating chambers 20 by means of connecting circulating pipes 27.

In the modification in Fig. 3, a portion of a water circulating and cone shaped cap 28 is shown, constructed similarly to the cone cap 11 and having in lieu of the pipe connection 15 25 17, a tubular connection 29, formed of a strip of metal 30 soldered to the top of the cap.

Having described the invention we claim.

1. In a water heater of the character described a plurality of conical heating chambers 30 with open ends at the top and bottom, and located side by side; said heating chambers diverging downwards, and outwards from their tops, and having a spiral water channel in their walls; and a spiral water 35 circulating and heating cone capped connection mounted over, and connected to the upper ends of the conical heating chambers.

2. In a water heater of the character described, a plurality of conical water circulating and heating chambers with open ends 40 at top and bottom and located side by side; each having a spiral water circulating channel in its walls extending from top to bottom thereof; and a cone shaped spiral water 45 circulating channel capped connection mounted over, and connected to the upper end of the conical water circulating chambers.

3. A water heater of the character described, consisting of conical water circulating and heating chambers with open ends, and independently mounted adjacent to 50 each other; each cone consisting of concentric cones with a narrow space between them closed at its ends; the inner cone being 55 formed with spiral crimps bearing against the outer cone and forming a spiral water circulating channel; cone shaped water circulating and heating caps mounted over the tops of the conical heating chambers, and 60 each consisting of two concentric cone shaped

caps, with a narrow space between them closed at its lower end; the inner cap being formed with spiral crimps bearing against the outer cap, and forming a spiral water circulating channel; a pipe connection between the tops of the caps; and pipe connections between the caps and the spiral water channels in the heating cones. 65

4. A water heater of the character described, consisting of several heating cones, 70 with open ends, and independently mounted adjacent to each other; each cone having a spiral water circulating channel in its walls extending from top to bottom thereof; a water inlet pipe with drainage faucet connected to the lower end of the spiral channel of one of the heating cones; several cone shaped caps mounted above the tops of the heating cones; each cone having a spiral water circulating channel in its walls; a pipe 75 connecting the lower end of said channel in each cap with the channel in the heating cone; a pipe connecting the upper ends of the spiral channels in the caps; a pipe connecting the lower end of the spiral channel in each cap with the upper end of the spiral channel in the adjacent heating cone; an outlet pipe with drainage faucet connected with the lower end of the spiral channel in the adjacent heating cone; and a vertical pipe 80 connected with the outlet pipe, and having its upper discharge end located above the tops of the heating cones.

5. In a heater of the class described, hollow conical circulating members having 95 their walls formed each with a spiral water conduit, the said members being arranged side by side, a conical cap disposed above the upper ends of the members and having its walls formed also with a spiral water conduit, 100 a water inlet pipe communicating with one of the first mentioned heating members at the base thereof, a pipe establishing communication between the upper end of this member and the base of the conical cap, a 105 pipe leading from the apex of the conical cap and connecting with and leading into the upper end of the other conical member first mentioned, and a discharge pipe leading from the last mentioned member at the base 110 thereof.

In testimony that we claim the foregoing as our own, we have hereto affixed our signatures in the presence of two witnesses.
